COMBINATION ASHTRAY AND DISPLAY HOLDER

Filed May 6, 1940

Inventor:
John F. Schylander:

By: Hill & Hill Atty:

UNITED STATES PATENT OFFICE

2,285,365

COMBINATION ASH TRAY AND DISPLAY
HOLDER

John F. Schylander, Chicago, Ill.

Application May 6, 1940, Serial No. 333,626

4 Claims. (Cl. 40—156)

This invention relates to trays and the like, and particularly to the manner of mounting thereon and securing thereto, suitable decorative devices, such as initials, monograms, advertising matter and the like.

One object of the present invention is to provide a tray of suitable construction whereby a decorative device may be readily attached thereto.

Another object of the invention is to provide novel means for securing a decorative device in a holder capable of ready and convenient attachment to a tray.

Another object of the invention is to provide novel means for readily positioning a holder, containing a decorative device, with reference to a tray for attachment thereto, and wherein suitable means are provided for protecting the device from damage due to outside influence, such as fire, heat, washing of the tray or the like.

A further object of the invention is to provide a device of the character described, which is of simple construction, efficient, capable of being readily assembled, and economical to manufacture.

A still further object of the invention is to improve devices of the character described in sundry details hereinafter referred to and particularly pointed out in the appended claims.

One embodiment of the present invention is shown for illustrative purposes in the accompanying drawing, in which:

Fig. 1 is a plan view of a tray embodying features of the present invention, certain portions of the figure being broken away to better illustrate the structure embodied therein;

Fig. 2 is a sectional elevational view of the structure illustrated in Fig. 1, and taken substantially as indicated by the line 2—2 thereof; and

Fig. 3 is a sectional elevational view of a portion of the structure illustrated in Figs. 1 and 2, showing certain of the elements in a position prior to securing the elements to each other and in position on the tray.

As illustrated in the accompanying drawing, the present invention comprises a tray indicated, as a whole, by the numeral 5 and shown, in the present instance, as being suitable for use as an ash tray, having a saucer-like base portion 6 provided adjacent its marginal edge with a flange 7 having depressions 8 formed therein adapted to receive a cigar, cigarette, or the like, as is common practice in devices of the character described.

The bottom portion of the saucer-like base 6 is shown, in the present instance, as provided

with an annular rib 9 extending upwardly from the base and surrounding the central portion 11 thereof, which is clearly shown in Fig. 2 as being offset vertically from the plane of the remaining portion of the base 6 outside of the rib 9.

For mounting a suitable decorative device, such for example, as initials, monograms, advertising matter or the like on the tray, a vertically disposed hollow member 12 shown, in the present instance, as of annular form, is provided with an inwardly extending flange 13 adjacent its upper edge portion and having a transparent plate or member 14 such, for example, as glass, crystal, mica, or the like, positioned within the vertically disposed hollow member 12 and against the under side of the flange 13, the transparent member 14 being shown, in the present instance, preferably of dome shape, adapted to extend, adjacent its central portion, slightly above the upper edge of the member 12.

Positioned also in the member 12 is a substantially disc-like member 15, preferably of relatively stiff paper, such as cardboard or the like, which may be suitably curved, and on which a suitable decorative device or indicia, such as initials, monograms, advertising matter, or the like, may be printed or otherwise attached to the side thereof adjacent the crystal 14 in a manner to be visible therethrough.

For securing the crystal 14 and disc-like member 15 in the member 12 and adjacent the flange 13 thereof, a dished ring-like retainer 16 having an opening 17 adjacent its central portion is positioned within the member 12 with the outer edge portions of the retainer 16 closely adjacent the side walls of the member 12, as illustrated in Fig. 3, after which the portion of the retainer 16 adjacent and surrounding the opening 17 formed therein is bent or pressed toward the plane of the outer edge portions of the retainer and disc 15, as illustrated in Fig. 2, thereby causing a stretching or expansion of the retainer radially to force the outer edge portion thereof snugly against the wall of the member 12 in a manner to provide a binding frictional engagement therewith for securing the retainer 16, disc 15, and crystal 14 adjacent the upper edge portion of the member 12.

For securing the member 12 and elements mounted therein to the base 6 of the tray, the offset portion 11 of the tray bottom is provided, preferably within and adjacent the rib 9, with a plurality of preferably elongated, radially disposed, annularly spaced apertures 18 adapted to receive correspondingly spaced lugs 19 formed on

the lower edge portion of the annular wall of the member 12, after which the lugs 19 are bent inwardly, as clearly illustrated in Fig. 2, and in a manner to occupy a position substantially in the plane of the portion of the bottom 6 outside the rib 9.

It will be observed that by reason of the arrangement of the apertures 18 with respect to the rib 9, the lugs 19 may be readily positioned in the apertures 18 merely by positioning the lugs within the rib 9 and rotating the member 12 to the proper position where the lugs 19 will register with and enter the apertures 18, thereby facilitating assembly of the member 12 with the tray bottom.

For suitably protecting a desk, table, or the like on which the tray may be placed, a pad 21 of felt or other suitable material, may be positioned on the extreme lower portion of the tray, as illustrated in Fig. 2.

It will be apparent from the foregoing description that the present invention provides a novel construction and arrangement whereby a suitable decorative device may be readily and conveniently attached to a tray, and wherein suitable means are provided for protecting the decorative device from damage.

It will be apparent also that the present invention provides novel means for securing a decorative or other similar device in a member capable of convenient attachment to a tray, and wherein suitable means are provided for positioning the member with respect to the tray for attachment thereto.

Obviously, the present invention is not limited to the precise construction and arrangement shown and described, as the same may be variously modified without departing from the spirit and scope of the invention as set forth in the appended claims.

What I claim as new and desire to secure by Letters Patent is:

1. In an article of the class described and in combination, a saucer-like base, the central portion of the bottom of said base being offset and positioned above the outer portion of the said bottom and providing a plurality of circumferentially arranged apertures adjacent its marginal edge, a vertically disposed annular hollow member, a plurality of detent members projecting from said hollow member and respectively extending through said apertures and having their free ends inturned, said member having an inwardly extending flange formed thereon adjacent its upper edge portion, a transparent dome-like member positioned in said annular member adjacent said flange, a disc having indicia thereon adjacent the inner side of said dome-like member, and expansible ring-like means engageable with the inner wall of said hollow member for securing said dome-like member and disc therein.

2. In an article of the class described and in combination, a saucer-like base having an upwardly extending annular rib formed in the bottom thereof and surrounding a central portion of said bottom, the portion of the bottom within

said rib being offset from the plane of other portions of said bottom, said offset portion having a plurality of radially disposed annularly spaced apertures therein adjacent said rib, an annular

5 hollow member having annularly spaced lugs adjacent its lower edge extending through said apertures and bent beneath said offset portion, an inwardly extending flange adjacent the upper edge portion of said member, a transparent crystal in said member adjacent said flange, and an expansible retainer having an opening adjacent its central portion, said retainer being positioned in said member with its outer edge adjacent the inner wall of the member and having that portion of the retainer surrounding the opening therein bent toward the plane of the outer edge portion thereof to expand said outer edge of the retainer against the inner wall of said hollow member for securing said crystal adjacent 10 said flange.

3. In an article of the class described and in combination, a saucer-like base having an upwardly extending annular rib formed adjacent the central portion thereof, the bottom portion of the base within said rib offset from the plane of the portion of the bottom outside said rib, said offset portion having a plurality of radially disposed annularly spaced apertures therein, an annular hollow member having annularly spaced lugs formed integrally therewith adjacent its lower edge extending through said apertures and bent beneath said offset portion for securing said hollow member thereto, an inwardly extending flange adjacent the upper edge portion of said member, a transparent crystal within said member adjacent said flange, a disc within said member adjacent said crystal, and a dished ring-like retainer having an opening adjacent its central portion, said retainer being positioned within said member with its outer edge adjacent the inner wall thereof and said disc, and having that portion of the retainer surrounding said opening bent toward the plane of said disc and outer edge portion of the retainer to expand said outer edge thereof radially against the inner wall of said hollow member for securing said crystal and disc adjacent said flange.

4. In an article of the kind described and in combination, a base, a vertically disposed hollow cylindrical member secured to the base adjacent the central portion thereof, said member having an inwardly extending flange adjacent its upper edge portion, a transparent member positioned in said hollow member adjacent said flange, a disc having indicia thereon and engaging the inner side of said transparent member, and a resilient annular member positioned within said hollow member for securing said transparent member and disc in position, said plate having an outer diameter normally greater than the inner diameter of the hollow member and being distorted to a concavo-convex cross section along radial lines in an amount such that its outer peripheral edge engages said disc and presses against the inner face of said hollow member.

JOHN F. SCHYLANDER.
